G. F. Folsom. Sheet 1 of 2 Sheets
Printing Press. Patented Apr. 1, 1856.

G. F. Folsom
Printing Press.
N° 14558. Patented Apr. 1, 1856

Sheet 2 of Sheet 2

UNITED STATES PATENT OFFICE.

GEORGE F. FOLSOM, OF ROXBURY, MASSACHUSETTS.

IMPROVED PRINTING-PRESS.

Specification forming part of Letters Patent No. 14,558, dated April 1, 1856.

To all whom it may concern:

Be it known that I, GEORGE F. FOLSOM, of Roxbury, in the county of Norfolk and State of Massachusetts, have invented certain new and useful Improvements in Printing-Presses, of which the following is a full, clear, and exact description, reference being had to the annexed drawings, making part of this specification, in which—

Figure 1 is a plan; Fig. 2, a side view; Fig. 3, a longitudinal section upon the line A A of Fig. 1; Figs. 4, 5, 6, 7, 8, and 9, detached views, which will be referred to hereinafter.

The nature of my invention consists in the use of two bed-plates and two platens in the same machine, in combination with an endless rotary paper-carrier, by means of which the paper after being printed upon one side is carried to the other form and printed upon the opposite side, the paper leaving the machine printed upon both sides.

To enable others skilled in the art to understand my invention, I will proceed to describe the manner in which I have carried it out.

In the accompanying drawings, B is the frame-work of the press.

C C' are two stationary bed-plates secured to the standards D.

E E' are the platens, their shaft F F' sliding vertically in the bearings G G'. These platens are made simultaneously to approach the bed-plates at the required intervals to give the impressions in the following manner:

H is a shaft to which the power is applied which drives the press. I are pinions upon each end of this shaft (seen in red in Figs. 1 and 2) and which engage with cog-wheels K, each of which carries two cranks a, cast in one piece therewith. These wheels, with their cranks, are seen detached in Fig. 5.

L L' are pitmen, which communicate motion from the cranks a to the cross-heads M M', by which means as the shaft H revolves the platens are made to approach the bed-plates C C' and the impression is given. The cog-wheels K are secured to the shaft N. The platens E E' are separated from the bed-plates after the impression is made by the springs O O', the ends of which bear upon the frame of the machine.

The forms are secured the lower one to the platen E', and the upper one to the bed-plate C. The types are inked in the following manner: P are endless chains which run

upon the carrying-wheels Q and to which the feeding-nippers and the inking-rollers are attached. In the press represented in the accompanying drawings there are five sets of ink-rolls c and nippers d, which are attached to the carriers b upon the endless chain P. This chain receives an intermittent motion in one direction in the following manner: R is a cog-wheel, which engages with the pinion I and drives the cog-wheel S. This latter wheel engages with the wheel T upon the shaft U. This shaft carries near its center an eccentric V, Fig. 3, which actuates a lifter-toe W upon the shaft X. Y is an arm secured to this shaft, which carries a cogged segment Z. This latter engages with a gear A', which runs loosely upon the shaft d and is seen in red in Figs. 2 and 3 and in blue in Fig. 7. F is a pawl attached to one of the carrying-wheels Q, which are secured to the shaft d and revolve with it. e is a spring which keeps the pawl in contact with the teeth of the wheel A'. As, now, this latter wheel is revolved in the direction of the arrow by the cogged segment Z it carries with it the carriers Q and the endless chain P. When it is revolved in the other direction by the return of the segment Z, no motion is communicated to the carrier Q. g is a retaining-pawl attached to the frame-work which engages with the ratchet-wheel i, secured to the shaft d, by which means this shaft and its carriers Q are held stationary while the segment Z returns. This return of the segment is effected by the spring H', one end of which is secured to the frame-work at k and the other to the shaft X.

I will now describe the manner in which the paper is fed to the nippers. M² is a lever pivoted to the frame-work and connected by the rod N' to the vibrating segment Z. At the other end it carries a pawl l, which engages with a ratchet-wheel upon the feed-roll P'. As the segment Z vibrates to feed forward the chain, motion is thus communicated to the feed-apron Q', which passes over the roller s, running in the arms r, as seen in Figs. 1, 2, and 3. T' is a presser rod or binder which is supported by the arms q and is borne down upon the feed-apron by the spring a². The paper is now arranged in parcels of twenty sheets, more or less, as seen in Fig. 8, each sheet projecting beyond the one beneath it an amount equal to the distance fed by the apron each time it is set in

motion. The paper thus arranged is placed upon the feed-apron, so that the presser-rod T' shall bear upon the uppermost edge of the top sheet, as seen in Figs. 1 and 8. The feed-apron being now set in motion, the paper is carried forward sufficiently far to free the top sheet from the presser-rod T' and to bring it into position to be seized by the nippers d , which remain stationary immediately in advance of the apron to receive it. The paper having been thus fed forward hangs a short distance over the end of the feed-apron, and at the required instant is placed in the nippers in the following manner: m is a shaft which runs in stationary boxes in the frame and upon which rest the arms r , which carry the feeding-apron. The latter is thus kept up out of the way of the ink-rollers and nippers, as seen in Figs. 2 and 3, which are allowed to pass freely beneath it. The instant after the passage of the nippers the projecting edge O^2 of the sheet of paper is placed therein, the apron being caused to drop sufficiently for the purpose in the following manner: I' is a pulley upon the shaft U , which communicates motion through the band K' to the pulley L' upon the shaft m . This shaft is so cut away at the point where the arms r rest thereon, as seen in Fig. 9, that at a certain instant in its revolution, when the notch n comes opposite to the notch p in the arms r , the latter shall drop a sufficient distance to enter the sheet of paper into the nippers, which now start forward with this sheet, the presser-rod T' bearing upon the upper edge of the next sheet, and thus but one sheet is carried at any one time into the machine.

Any suitable form of nippers may be made use of for carrying the paper into the machine, but as this forms no part of my present invention the details of these nippers need not be further described.

In Fig. 6 is seen the device by which the nippers are opened for the purpose of dropping the printed sheet. R' (seen also in position in Fig. 3) is a hook which catches into a pin upon the nippers and opens them as they pass. The sheet being thus released falls upon the table B' beneath.

Operation: The paper being arranged in parcels of twelve to twenty sheets, as already described and as represented in Fig. 8, is placed upon the feed-apron, the rod T' bearing upon the upper edge of the top sheet. The paper is now fed forward by the backward motion of the segment Z a sufficient distance to free the top sheet from the presser-rod. The feed-apron being held up out of the way of the ink-roll by the shaft m , the rolls having passed from beneath the feed-apron, the notch n now passes the notch p in the arms r and the latter drop. The projecting edge O^2 of the paper is thus placed in the nippers, the presser-rod T' bearing upon the next sheet and preventing it from being drawn off with the one before it. The eccentric V now strikes against the lifting-toe W , and by the motion of the segment Z the chain, with the ink-rolls and nippers, is fed forward a sufficient distance to place the sheet of paper over the form upon the bed-plate C . While this is taking place another sheet, which the instant before was printed upon the bed-plate C , is carried over the form upon the platen E' , and as the shaft N continues to revolve the platen E is caused to descend and E' to ascend by the connections already explained, and an impression is taken from each form and the paper leaves the machine printed upon both sides. The nippers now are opened by the hook R' and the sheet is dropped upon the table B' .

What I claim as my invention, and desire to secure by Letters Patent, is—

1. The method herein described of giving the impressions with the two platens by means of the gear K and double cranks a , operating in the manner substantially as herein set forth.

2. The method herein described of feeding the sheets into the nippers by means of the binder T' , in combination with an intermittent feed, operating in the manner set forth.

GEORGE F. FOLSOM.
